UNITED STATES PATENT OFFICE.

CHARLES C. SPREEN, OF DETROIT, MICHIGAN.

REFRIGERATION.

Application filed January 10, 1927. Serial No. 160,297.

My invention relates to mechanical refrigeration, and particularly to containers for freezing substances under the action of the refrigerant expansion apparatus of mechanical refrigeration units, and the principal object of my invention is to provide a new and improved container of this type. In the drawings accompanying this specification and forming a part of this application I have shown, for purposes of illustration, certain forms which my invention may assume.

In these drawings:

Figure 1 is a top plan view of one embodiment my invention may assume.

Figure 2 is a cross section on the line 2—2 of Figure 1, while

Figure 3 is a cross section similar to Figure 2 showing another embodiment which my invention may assume.

The embodiment of my invention shown in Figures 1 and 2 comprises a tray 11 for the freezing of substances under the action of domestic mechanical refrigerating mechanism, provided with a grid 12 to subdivide the space within the tray 11 into a plurality of smaller spaces to subdivide the frozen substances into a plurality of cubes of a size suitable for table use.

The grid 12 consists of a plurality of longitudinal plates 13 and a plurality of transverse plates 14 having cooperating notches 15 and 16 at their points of intersection. Each of the notches 15 of the transverse plates 14 has at its closed end an angularly directed extension 17, while each of the notches 16 of the longitudinal plates 13 is provided with a tongue 18 adapted to be bent away from the plane of the plate 13 to seat within one of the angularly directed extensions 17 of the notches 15 in the plates 14 as the plates 13 and 14 are assembled, whereby the transverse plates 14 and longitudinal plates 13 will be firmly locked together when the plates 13 and 14 have been assembled in grid forming relation.

The embodiment of my invention shown in Figure 3 retains the longitudinal plates 13 and transverse plates 14 but provides the ends of the notches 15 in the plates 14 with curved offset portions 19 while the notches 16 of the plates 13 are provided with tongues

20 adapted to interlock with these curved offset portions 19.

From the above disclosure it will be obvious to those skilled in the art that I have provided new and improved means for freezing substances under the action of the refrigerating apparatus of domestic mechanical refrigeration mechanism, and accordingly that I have accomplished at least the principal object of my invention.

It will also be obvious to those skilled in the art that the particular embodiment of my invention herein shown and described may be variously changed and modified without departing from the spirit of my invention or sacrificing the advantages thereof, and it therefore will be understood that the disclosure herein is illustrative only and that my invention is not limited thereto.

I claim:

1. For use in connection with mechanical refrigeration refrigerant expansion apparatus, and for the freezing of substances under the action of said refrigerant expansion apparatus; a container formed to be received in and supported by said refrigerant expansion apparatus, and a grid for dividing the space within said container into a plurality of smaller spaces, comprising at least two sets of intersecting plates having cooperating notches at their points of intersection to permit assembly of said sets into said grid, each of said sets comprising at least one plate, and means to hold said plates assembled comprising offset extensions at the closed ends of one notch of each pair of cooperating notches, and tongues projecting into the closed ends of each cooperating notch deformable into said extensions upon assembly of said plates into said grid to thereafter hold said plates so assembled.

2. For use in connection with mechanical refrigeration refrigerant expansion apparatus, and for the freezing of substances under the action of said refrigerant expansion apparatus; a container formed to be received in and supported by said refrigerant expansion apparatus, and a grid for dividing the space within said container into a plurality of smaller spaces, comprising at least two sets of intersecting plates having cooperating

notches at their points of intersection to permit assembly of said sets into said grid, each of said sets comprising at least one plate, and said plates of one of said sets intersecting said plates of the other of said sets substantially at right angles, and means to hold said plates assembled comprising offset extensions at the closed ends of one notch of each pair of cooperating notches, and tongues

projecting into the closed ends of each co-¹⁰
operating notch deformable into said extensions upon assembly of said plates into said grid to thereafter hold said plates so assembled.

In testimony whereof I hereunto affix my signature.

CHARLES C. SPREEN.
